UNITED STATES PATENT OFFICE.

HARRY E. CAMPBELL, OF BALTIMORE, MARYLAND, ASSIGNOR TO CAMPBELL METAL WINDOW CORPORATION, OF BALTIMORE, MARYLAND, A CORPORATION OF MARYLAND.

WINDOW-SASH CONSTRUCTION.

Application filed March 25, 1927. Serial No. 178,194.

The present invention relates to window sashes of a type which may be used in a construction where the sashes have plates which extend through openings in the jamb 5 face into enlarged chambers within the jamb. A window of this type is fully described in my Patent No. 1,549,711 dated August 11th, 1925. While the sashes made by this invention are primarily intended for use in such 10 a window, they may also be slightly modified for use in other types of window and still include my invention. According to the present invention, the sashes are so built that the glass stops may be put in place without 15 the use of screws. At the same time, the method of manufacture is a highly economical one and will give a stiff sash even if light gauge metal is used.

In the accompanying drawings, I show 20 two forms of my invention. Fig. 1 is a section through a sash embodying one form of the invention primarily intended for use with fairly heavy metal; Fig. 2 is a plan view of a lower corner of the sash shown in 25 Fig. 1; Fig. 3 is a section through a sash made of flexible metal such as light gauge steel or bronze; Fig. 4 is a shadow view of a corner of a partially completed sash of the type shown in Fig. 3, and Fig. 5 is a reduced scale view showing of the manner in 30 which the glass stops are inserted in either of the foregoing forms.

As shown in Fig. 1, the sash is made up 35 of a plate 2 bent back on itself at 4 so as to leave a crack 6 between the two flat surfaces. An offset portion 8 is provided of the proper length to form a rabbet for the glass, and the plate is then bent on in the original direction at 10. As shown in Fig. 2 the corners of the sash are mitred and a triangular 40 piece 12 is inserted in the crack 6 of each adjacent section of the sash. The piece 12 is spot welded in place. In addition, the mitred joint may be spot or butt welded so as 45 to strengthen the mitred corners. The glass stop has a main portion 14 of a thickness just sufficient to squeeze into the crack 6, and is bent back on itself at 16, so as to strike against the offset portion 8 of the sash 50 thus limiting the distance that the glass stop can be pushed into the crack 6.

As shown in Fig. 5 the two upper corners 55 of the glass stops are mitred, whereas the side members come down straight and the bottom member fits in between the two side

members. In glazing the window, the glass stops are removed, the putty and glass put in place in the rabbet, then the top glass stop is pushed in as far as it will go, and the top of each side glass stop is put in 60 the corresponding crack 6 (as indicated in broken lines in Fig. 5) and pushed back into place as shown in full lines in Fig. 5 and as shown in Fig. 2. The bottom glass stop is then pushed down. Inasmuch as 65 there will be no tendency for the bottom stop to ride upward, these stops will all be locked into place without the use of screws. It may be noted that the main portion 14 of the glass stop does not extend all the way 70 to the bottom of crack 6. Thus if any putty works into this crack, it will be pushed towards the bottom when the glass stop is put in place and will not interfere with the glass stop. Also by having the members 2 and 4 75 connected a substantial distance from the position of the innermost edge of the glass stop, these members can advantageously be arranged to maintain a pinch or spring pressure on the glass stop.

In the form shown in Fig. 3 the sash 2' has a portion 4' corresponding to portion 4 and forming a crack 6', and has an offset portion 8' and a portion 10' corresponding to the portion 10. In addition, it has a 80 portion 11 bent back against the portion 10' and extending beyond the portion 8' leaving a crack 13 between the two. A member 15 is adapted to have one leg pushed into the crack 13 and completes a box-like structure to give rigidity to the sash. The member 15 may be held in place by a few spots of solder applied at spaced intervals. This 85 form of construction is particularly useful for light gauge metal of bronze.

In assembling the form of sash shown in Fig. 3, members 15 are cut away a short distance at the corner, thus leaving at each corner an opening extending into the box of the sash. A plug of putty as indicated at 90 17 is inserted in each channel and then after the sash is warmed, hot solder is poured into the channel and the corner squared out with the solder. A member 12' corresponding to the member 12 may also be used.

The glass stops 14' are similar to the glass stops 14 and are inserted in the manner already described.

What I claim is:

1. A window sash construction in which 110

each side of the sash frame comprises a sheet metal member bent to form a glass rabbet and bent to form a plate, parallel with the glass, which plate comprises two thicknesses of the metal spaced apart a small distance, and in which the glass stops comprise metal plates adapted to slip only part way into the spaces between said two thicknesses of metal and to be held in place by spring pressure.

2. A construction as specified in claim 1, in which the sash frame members are united at the corners by the aid of metal plates in the spaces between said two thicknesses of metal.

3. A window sash construction in which

the sides of the sash frame each comprises a sheet metal member bent to form a glass rabbet and bent to form a plate parallel with the plane of the glass, which plate comprises two thicknesses of the metal spaced apart a small distance and further includes a second member which together with a side of said plate and the side of the rabbet forms a box-like tube, and in which the glass stops comprise metal members adapted to slip into the spaces formed in said plates.

4. A construction as specified in claim 3, in which the sash frame members are united at the corners by the aid of solder poured into such box-like tubes.

HARRY E. CAMPBELL.
